United States Patent Office

Des. 211,291
Patented June 4, 1968

211,291

MICRO-IMAGE VIEWER UNIT

Charles T. Inatomi, Culver City, and Hideo Akiyama, Los Angeles, Calif., assignors to The National Cash Register Company, Dayton, Ohio, a corporation of Maryland

Filed June 29, 1967, Ser. No. 7,639

Term of patent 14 years

(Cl. D61—1)

FIG. 1

FIG. 2

FIG. 4

FIG. 3

FIG. 5

FIG. 1 is a front perspective view of a micro-image viewer unit showing our new design.

FIG. 2 is a right side elevational view of the same.

FIG. 3 is a left side elevational view of the same.

FIG. 4 is a top plan view of the same.

FIG. 5 is a rear view of the same.

We claim:

The ornamental design for a micro-image viewer unit, substantially as shown.
